HANDLE CAP FOR BRUSHES AND THE LIKE

Jeffrey Snyder, 5225 Collins Ave.,
Miami Beach, Fla. 33140

Original design application July 3, 1973, Ser. No. 376,150.
Divided and this application Sept. 9, 1974, Ser. No.
504,046

Term of patent 14 years

Int. Cl. D4—01

U.S. Cl. D4—4

FIG. 1.

FIG. 2.

FIG. 3.

FIG. 1 is a side elevational view of a handle cap for brushes and the like, showing my new design;

FIG. 2 is a front perspective view thereof; and

FIG. 3 is a rear perspective view thereof.

The portion of a wall-mountable rack shown in broken lines in FIG. 1 is for illustrative purposes only and forms no part of the claimed design.

This application is a division of design application Ser. No. 376,150 filed July 3, 1973.

I claim:

The ornamental design for a handle cap for brushes and the like, as shown and described.
